LUGGAGE EDGE-BINDING INTEGRAL STRIP
OF RUBBERY MATERIALLaurence H. Chenoweth, Akron, Ohio, assignor
to The B. F. Goodrich Company, New York,
N. Y., a corporation of New York

Application April 30, 1945, Serial No. 591,198

4 Claims. (Cl. 190—37)

1

This invention relates to receptacles for materials and especially to such receptacles having corner constructions with protective binding strips and to such binding strips.

Prior constructions of receptacles or containers for materials and/or articles such, for example, as travelers' personal baggage for clothing and other articles, have generally used binding strips of leather, treated or untreated woven fabric, metal and other related materials at the corner constructions of such baggage for reinforcing and protecting the same. However, such receptacle constructions have not been wholly satisfactory for the purpose intended because of their deficient cushioning properties and because the binding strips have torn loose, broken, ripped or otherwise failed after usage and exposure to the weather, due to, for example, the deterioration of such materials as to their tension and compression, resistance to wear, resistance to tear, resistance to chemical agents, appearance, and other characteristics.

Objects of the invention are to provide an improved receptacle or luggage binding strip for the corners or edges of the receptacle or luggage; to provide for forming the strip as an elastic integral strip of rubbery plasticized thermoplastic material; to provide for cushioning blows against the luggage at the corners or edges thereof; to provide for sealing and protecting effectively the corners or edges of the luggage; to provide for attaching securely the binding strip to the luggage; to provide for maintaining the appearance of the luggage at the corners or edges thereof; and to provide for convenience of manufacture, simplicity of construction, and for effectiveness of operation.

These and other objects and advantages of the invention will be apparent from the following description.

In the accompanying drawings, which form a part of this specification and in which like numerals are employed to designate like parts throughout the same,

Fig. 1 is a perspective front view from above of a receptacle constructed in accordance with and embodying the invention, and

Fig. 2 is a sectional view taken along line 2—2 of Fig. 1, parts being broken away.

In the illustrative form of the invention shown in the drawings, a receptacle or container 5 suitable, especially, for use as travelers' baggage for containing clothing and other articles and materials, is of the portable, hand-carried type hav-

2

ing, desirably, a closable mouth and a relatively flexible wall construction. Such walls may be of leather or woven fabric coated or otherwise treated with suitable strengthening and waterproofing materials such, for example, as rubber or other rubber-like material. However, it is to be understood that the invention is equally applicable to receptacles having walls of relatively stiff material such, for example, as Bakelite and other plastics, wood, sheet metal, and compositions as, for example, plywood, plastic wood and other related materials having the required strength, weight, resistance to abrasive wear, appearance, and other desired characteristics.

10 The receptacle 5 includes spaced-apart side walls 6 and 7 interconnected by end walls 8 and 9 and a bottom wall 10, which bottom wall may be reinforced for stiffening purposes. The walls are suitably joined at their adjacent margins as

15 by sewing 11 or by an adhesive suitable for the purpose, or by both, for providing a unitary receptacle construction having an open-mouth arrangement at the top of such receptacle. For

20 facilitating closing such open-mouth, the side wall 7 may be provided with an extension 12 adapted to be positioned over the opening and secured to the opposite side wall 6 as by a suitable snap fastener means 13. Handles 14, 15 of suitable material in strip form may be provided for conveniently carrying the receptacle or package, end portions of each handle being attached to one of the side walls as by sewing 16, 16 and overlying reinforcing patches 17, 17 of suitable material, as shown especially in Fig. 1 for the handle 14.

25 For the arrangement shown in the drawings, the bottom wall 10 is in angular relation to and converges toward the respective sides 6, 7 and ends 8, 9 of the receptacle, providing a continuous corner zone at the intersection of such walls about the periphery of the bottom of the receptacle.

30 To the end of sealing and protecting the corner construction continuously about such periphery, the invention provides a flexible binding strip 18, preferably elastic at least in portions thereof, and being of rubbery material which may be plasticized thermoplastic material, reinforced or unreinforced as desired, though preferably without fabric or other reinforcement. Such binding strip 18 is positioned continuously along

35 such corner zone about the bottom periphery of the receptacle. While the binding strip 18 is shown applied about the corner zone periphery at the bottom of the receptacle, such binding strip 55 may be applied, if desired, at corner zones pro-

vided by the intersections of the end walls with the side walls of the receptacle as well as at other corner zone locations in the structure of the receptacle, for protective purposes.

The preferred material of the binding strip 18 is plasticized polyvinyl chloride or polymer made from vinyl chloride together with minor proportions of other polymerizable materials such as vinyl acetate, acrylic esters, vinylidene chloride and the like. The polymer may be plasticized with any of the non-volatile liquid plasticizers ordinarily used for this purpose, such as tricresyl phosphate, dibutyl phthalate, dibenzyl sebacate, butyl phthalyl butyl glycolate, and the like, or with rubbery materials compatible with the polymer, such as the butadiene-acrylonitrile synthetic rubbers, or with mixtures of such materials.

The hereinabove described material of the binding strip provides the desired characteristics of strength, elasticity, including stretchability and resilience, and resistance to aging and swelling, in addition to being highly resistant to wear, to tear, to objectionable distortion, and to many chemical agents such, for example, as sulphuric, nitric and chromic acids, gasoline, naphtha, carbon tetrachloride, and other solvents, and also strong alkalis. The material is also relatively impervious to water and may be prepared in a variety of colors, the colors in the strips being uniform throughout. This permits the production of contrasting color effects, when desired.

The binding strip 18 may be generally L-shape in cross-section, as shown especially in Fig. 2, and may be extruded, molded, or otherwise formed to such shape, preferably in strip form, for convenience of assembly purposes. Such binding strip 18 includes a projecting flange or marginal portion 19 overlying the outer surface of and being attached to one of the intersecting walls forming the corner zone, a second projecting flange or marginal portion 20 overlying the outer surface of and being attached to the other intersecting wall, and a cushion and bumper tubular or outwardly extending convex hollow portion 21 intermediate such flange portions positioned immediately at the intersection of the walls, which tubular portion 21 preferably has an arcuate convex outer wall 22, which wall may project outwardly with respect to such intersecting walls of the receptacle for functioning as a resilient bumper. Preferably, the tubular portion 21 has a continuously annular tubular wall defining a bore extending, desirably, continuously throughout the longitudinal extent of the binding strip.

In assembling the binding strip with the receptacle, such flexible strip readily conforms to the surfaces of the walls at such corner zone, especially at regions of sharp curvature as at 23, 24, the strip stretching largely within itself to accommodate such sharp curvature by virtue of the stretchability of the rubbery plasticized thermoplastic material thereof. The binding strip may be attached to the respective walls of the corner zone as by lines of stitching 25 and 26 through the flange portions and the flexible walls of the receptacle or by any of the well-known adhesives suitable for this purpose, or both. For a receptacle construction having walls with an outer surface of material to which the material of the binding strip will fuse, such binding strip may be secured to such walls as by heating, for example, by the application of a hot iron, or by a well-known electronic high frequency stitching procedure, or even by flame working, whereby the

abutting surfaces of the walls and the binding strip are heated and fused together.

The respective ends of the binding strip 18 are desirably fused together or heat-sealed as at 27 as by heating the exposed adjacent surfaces of such ends with a hot iron and then pressing such ends together, thereby providing a jointless strip construction. Thus is avoided the danger that a joint may give way more or less as sometimes happens with jointed leather binding strips, for example. The tubular portion 21 including the substantially unrestricted and sealed air space therein extends continuously around the periphery of the corner zone, and by virtue of its resiliency and tubular construction provides effectively a bumper action for cushioning blows upon the receptacle, to further protect such corner construction against accidental damage.

Although the binding strip may, if desired, include a suitable fabric reinforcement therein, it is preferred that such reinforcement be omitted, so that the strip may be of a single material having uniform texture and color throughout for facilitating maintaining the appearance of the receptacle, especially at such corner zone, despite abrasion of the binding strip from scuffing or other damaging action.

By virtue of the described characteristics of the material of the binding strip and the construction and arrangement at the corner zone, the invention effectively protects and seals the corners of receptacles and also facilitates the provision of a jointless binding strip and the secure attachment of the binding strip to the walls. The invention thus makes possible a receptacle capable of withstanding relatively severe and extended service, while protecting the contents of such receptacle against accidental damage by seepage of liquid through the corner constructions and also maintaining the appearance of such corner constructions despite abrasive wear thereon.

Variations may be made without departing from the scope of the invention as it is defined in the following claims.

I claim:

1. A luggage edge-binding strip comprising rubbery plasticized polyvinyl chloride having the characteristics of toughness, impermeability, stitch-retaining capacity, heat-sealing ability, uniform color and texture, and resistance to abrasion and aging, said strip comprising flange portions projecting laterally of the strip in angular relation one to the other for attachment to adjoining walls of the luggage at an edge of the luggage, and a cushion and bumper portion intermediate said flange portions for positioning at said edge, the cushion and bumper portion being hollow to define an air space extending along said strip, and said flange portions and said cushion and bumper portion being formed as an integral strip of said plasticized polyvinyl chloride.

2. A luggage edge-binding strip comprising a rubbery plasticized polymer comprising vinyl chloride and having the characteristics of toughness, impermeability, stitch-retaining capacity, heat-sealing ability, uniform color and texture, and resistance to abrasion and aging, said strip comprising an intermediate cushion portion having flanges projecting laterally therefrom along said strip, said flanges and said cushion portion being formed as an integral strip of said plasticized polymer for mounting as a unit at the edge

ing the edge and said flanges extending along the adjoining walls of the luggage, and said cushion portion being hollow to define an air space extending along said strip and being relatively thick as compared to said flanges to protrude therefrom locally at the edge of the luggage in guarding relation to said flanges in the mounted condition of said strip.

3. A luggage edge-binding strip comprising a rubbery plasticized polymer comprising vinyl chloride and having the characteristics of toughness, impermeability, stitch-retaining capacity, heat-sealing ability, uniform color and texture, and resistance to abrasion and aging, said strip comprising an intermediate cushion portion having flanges projecting laterally therefrom along said strip, said flanges and said cushion portion being formed as an integral strip of said plasticized polymer for mounting as a unit at the edge of the luggage with said cushion portion overlying the edge and said flanges extending along the adjoining walls of the luggage, said cushion portion being of tubular form with a flexible inner wall between said flanges for flexure about and conformance to the edge of the luggage and said cushion portion being relatively thick as compared to said flanges and protruding therefrom locally at the edge of the luggage in guarding relation to said flanges in the mounted condition of said strip.

4. A receptacle edge binding strip angular in cross-section comprising rubbery plasticized polyvinyl chloride having the characteristics of toughness, impermeability, stitch-retaining capacity, heat-sealing ability, uniform color and
